UNITED STATES PATENT OFFICE

2,411,974

CAR BRAKE

Louis G. Miller and Walter H. Statler, Bethlehem, Pa., assignors to Bethlehem Steel Company, a corporation of Pennsylvania

Application May 12, 1943, Serial No. 486,628

9 Claims. (Cl. 188—55)

1

This invention relates to brakes for trucks used with industrial cars generally and in particular to mine cars of the large capacity type carried on a plurality of independent trucks.

Due to the modern trend toward mechanized mining and long hauls from loading to unloading points, it has become necessary for economical operation to utilize large capacity cars carrying in the neighborhood of ten tons or more of coal or other material. In attempting to build large capacity cars, it has been found impossible to merely enlarge the present type of car, for to do so produces an unwieldy car of excessive weight and a car which is incapable of negotiating the sharp curves occurring in the mines. It is an object, therefore, of the present invention to provide a brake for a truck for large capacity cars of this type with independent trucks at each end of the car.

It is therefore a primary object of this invention to provide for vehicles and particularly for mine cars, a braking mechanism which will be simple of construction, easy and safe of operation and positive in its action in applying the braking force to each wheel.

Another object of our invention is to equally distribute the braking force to all the wheels in the truck.

A further object of our invention relates to the manner of offsetting the ends of the brake beam and connecting the brake levers and brake shoes together instead of supporting them individually as is the usual practice.

With the foregoing and other objects in view, the invention will be more fully described hereinafter, and will be more particularly pointed out in the appended claims.

Having thus given a general description of the objects of our invention, we will now in order to make the same more clear, refer to the accompanying four sheets of drawings forming a part of this specification and in which like characters of reference indicate like parts.

Figure 1 is a top plan view of a truck with our improved brake mechanism applied thereto illustrating the application of our invention.

Fig. 2 is a side elevation of the truck and brake mechanism shown in Fig. 1.

Fig. 3 is an enlarged detail section taken on the line 3—3 of Fig. 4.

Fig. 4 is an enlarged detail section taken on the line 4—4 of Fig. 2.

Fig. 5 illustrates a horizontally inclined operating lever and connections mounted on the end of the car which is indicated in dotted lines.

2

Fig. 6 is a detail view of the brake equalizer bar and connecting parts adjacent thereto.

Fig. 7 is a detail section taken on the line 7—7 of Fig. 6.

Fig. 8 is a detail section taken on the line 8—8 of Fig. 6.

Fig. 9 is a detail showing the clevis connection and adjacent parts at one end of the operating lever.

Fig. 10 illustrates a modified form of operating lever of bell crank shape pivoted to the end of the car.

Fig. 11 is a detail section taken on the line 11—11 of Fig. 10, and Fig. 12 is a detail section taken on the line 12—12 of Fig. 10.

Referring to the accompanying drawings and first to Figs. 1 to 9 inclusive the two side frames of the truck, which are of similar construction, are formed of rolled plate sections cut in the desired shape and welded together. Each consists of a pressed Z-shaped side frame member 1 of considerable depth having a vertical web 2 with the top flange 3 extending outwardly and the bottom flange 4, inwardly and parallel with the top flange 3 throughout its length. The bottom flanges 4 of the two side frames support the ends of a centrally disposed spring plank 5 of channel shape and connects the side frame members together at this point.

30 The lower portion of the ends of each Z-shaped side frame member is cut away as at 6 and the web 2 recessed as at 7. Each recess is adapted to receive an inverted U-shaped bearing box 8 for the axles 9. These inverted U-shaped bearing boxes 8 have one leg 10 longer than the other and are welded to the web 2 and the bottom flange 4 of the side frame and are adapted to straddle the axles 9 and tie the ends of the side frames and axles together and transmit the load to the axles.

40 These bearing boxes 8 each have a bottom tie plate 11 welded to the legs so that in case of derailment the axles will not become disengaged from the side frame. Each bearing box 8 and web 2 of the side frames are further reinforced by means of vertical and longitudinally extending plates 12 and 13 respectively.

Adjacent to the center of each side frame vertically inwardly extending plate members 14 are placed on each side of the bolster 15 and spring plank 5. These vertical inwardly extending plate members 14 have a flanged top portion 16 and are welded to the side frames and are adapted to take the side thrusts of the bolster 15 and the spring plank 5 and maintain the truck in alignment.

55 The plate members 14 form column guides for

the ends of the bolster and are further provided with wear plates 17 for this purpose.

As shown in Fig. 2 the axles 9 are adapted to have a slight vertical movement in the bearing boxes 8 and the wheels 18 are mounted on the ends of the axles at the outer sides of the side frames as indicated in Fig. 1.

The brake beams 19 each consisting of round bar having their ends offset as at 20 and extending through elongated openings 21 in the webs of the side frame members and to allow clearance for the horizontal movement of the brake beams the vertically inwardly extending plates 14 are cut out as at 22, and the horizontally longitudinally extending stiffening plates 13 prevent the brake beams 19 from turning.

The offset ends 20 of the brake beams 19 extend beyond the outer sides of truck frame members 1 and are pivotally connected directly to the brake levers and brake shoes.

It will be understood that the linkage associated therewith is similar on each side of the truck and a description of one set will apply to both. The brake shoes 23 are pivotally secured on the ends of the brake beams and are further supported by means of brake hanger links 24 which are pivoted at their lower ends as at 25 to the brake shoes and have their upper ends pivoted as at 26 to L-shaped brackets 27 which are welded to the top flange 3 of the side frame member 1. The ends of each of the brake beams are also provided with a washer 28 and cotter pin 29 for retaining the brake shoes in position.

The live and dead brake levers 30 and 31 respectively are held in spaced relation with the brake shoes 23 by sleeves 32 and the web 2 of the side frame members 1 by means of sleeves 33. A link 34 having a U-shaped end 35, is pivoted by means of a pin 36 to the upper end of the dead brake lever 31, while the opposite straight end of said link 34 is attached to a pivotal bracket 37 which is secured to the web 2 of the side frame 1.

The lower ends of the live and dead brake levers are connected together by means of a coupling bar 38 which is pivotally attached thereto. A clevis 39 is pivoted to the upper end of the live brake lever 30 which is pivoted to one end of a brake equalizer bar 40. This brake equalizer bar extends through slots 41 in the webs 2 of the side frames and has its opposite end pivoted in a similar manner to the top of the live brake lever on the opposite side of the truck, and this brake equalizer bar is further supported on wear plates 42 secured to the webs 2 of the side frames adjacent to the slots 41. The central portion of the brake equalizer bar 40 is formed with an arc-shaped track 43 engaged by a roller 44 mounted between the ends of a pair of links 45 forming a pull rod, said pair of links having their opposite ends pivoted to the intermediate portion of a swinging lever 46 which is pivoted at its inner end as at 47 to a U-shaped bracket 48 connected to the car underframe, while the outer end of the swinging lever 46 is formed with a hook 49 to engage a guide plate 50 which is also attached to the car underframe. One end of a chain 51 is attached to the swinging lever 46 at a point beneath the guide plate 50 by means of a pin 52. The chain 51 passes over a guiding sheave 53 and extends to the end of the car having its opposite end attached to one end of a helical spring 54, which has its opposite end attached to a clevis 55 pivotally attached as at 56 to a horizontally inclined operating lever 57. This operating lever 57 is pivoted to the car end as at 58 and is pro-

vided with a tooth 59 for engaging a rack 60. As indicated in Fig. 5, the operating lever 57 is shown in full lines in the raised position as it will be when the brake is released, and to insure that the operating lever will be held in this position a projecting rivet 61 is secured to the car end wall as is the usual practice. When it is desired to set the brakes the operator grasps the handle 62 of the lever and manually raises it slightly and then moves it laterally to clear the rivet head or until it engages the keeper 63 and then swings said lever downwardly until it assumes the position indicated in dotted lines. When the brakes are set the spring 54 will be extended whereby the brake shoes will be held resiliently in contact with the treads of the wheels.

In Figs. 10 to 12 inclusive we have shown a modified form of operating lever 64 of bell crank shape pivotally attached to the end of the car as at 65, having a tooth 66 for engaging a rack 67.

In this construction we have used an additional guide sheave 68 for the chain 51. In this modification the braking force will be applied horizontally on the operating lever which might be preferred in some cases, instead of vertically as indicated in Fig. 5, otherwise the operation is substantially the same as described for Figs. 1 to 9 inclusive, and the same reference numerals will apply thereto.

30 Although we have shown and described our invention in considerable detail, we do not wish to be limited to the exact and specific details shown and described, but may use such substitutions, modifications or equivalents thereof, as
35 are embraced within the scope of our invention or as are pointed out in the claims.

Having thus described our invention what we claim as new and desire to secure by Letters Patent is:

1. In a brake rigging for railway car trucks having side frames and two pairs of wheels, a brake beam at one side of each pair of wheels extending through and supported by said side frames, a brake lever and brake shoe having their central portions mounted directly on each extending end of the brake beams at opposite outer sides of the truck frame, means for directly connecting the lower ends of the brake levers together on each outer side of the truck frame, and means connected to the upper end of one pair of brake levers for actuating the brake levers.
  2. In a brake rigging for railway car trucks having side frames and two pairs of wheels, a brake beam disposed adjacent to the inner side of each pair of wheels extending through and supported by said side frames, a brake lever and brake shoe having their central portions pivotally mounted directly on each extending end of the brake beams at opposite outer sides of the truck frame, a coupling bar directly connecting the lower ends of the brake levers together on each outer side of the truck frame, and means connected to the upper end of one of the brake levers on each side of the truck for actuating the truck levers.
  3. In a brake rigging for railway car trucks having side frames and pairs of wheels, a brake beam disposed adjacent to the inner side of each pair of wheels extending through and supported by said side frames, a brake lever and brake shoe having their central portions mounted directly on each extending end of the brake beams adjacent to the outer surface of the side frame members, and an equalizer bar pivoted to and

connecting the upper ends of a pair of brake levers having means for actuating the break levers.

4. In a railway brake, a truck frame, two pairs of wheels located beyond the outer sides of the truck frame for supporting said truck frame, brake beams having their ends extending through the sides of the truck frame and disposed adjacent to the inner side of each pair of wheels, a dead brake lever pivoted centrally directly on each extending end portion of one of the brake beams on each outer side of the truck, a live brake lever pivoted centrally directly on each extending end portion of the other brake beam on each outer side of the truck, a bar directly connecting the lower ends of the dead and live brake levers on each outer side of the truck, a pivotal connection between the top end of each dead lever and the truck frame, a brake equalizer bar extending through the truck side frames and supported therein having an arc shaped track connecting the top ends of the live brake levers, a pull rod having a roller mounted at one end for engaging the arc shaped track of the brake equalizer bar, a swinging lever pivotally attached to the other end of the pull rod, and an operating lever having a flexible connection with the swinging lever for actuating the brake mechanism.

5. In a railway brake, a truck side frame at each side of the truck, two pairs of wheels mounted adjacent to the outer side of the truck side frames, a brake beam extending through the side frames disposed adjacent to the inner side of each pair of wheels, a dead brake lever and a brake shoe mounted directly on the extending end portions of one of the brake beams outside the truck frame, a live brake lever and brake shoe mounted directly on the extending end portions of the other brake beam outside the truck frame, a direct connection between the lower ends of the dead and live brake levers at each side of the truck, a pivoted link connection between the top of each dead truck lever and the side frame, a brake equalizer bar extending through the side frames and supported therein connecting the upper ends of the live brake levers, and an operating lever having a flexible connection extending to the brake equalizer bar for actuating the brake mechanism.

6. In a brake rigging for railway car trucks having side frames and two pairs of wheels, a brake beam extending through and supported by the side frames disposed adjacent to the inner side of each pair of wheels, a dead and live brake lever mounted centrally directly on the extending ends of the brake beams at each outer side of the truck frame, means for directly connecting the lower ends of the dead and live brake levers on each outer side of the truck frame, a pivotal link connection between the top of each dead truck lever and the side frame, a brake equalizer bar extending through the side frame and supported therein connecting the top ends of the live brake levers together, and an operating lever having a flexible connection extending to the brake equalizer bar for actuating the brake mechanism.

7. In a brake rigging for railway car trucks having side frames and two pairs of wheels, a brake beam extending through and supported by the side frames having offset end portions disposed adjacent to the inner side of each pair of wheels, a dead brake lever and a brake shoe piv-

oted centrally in spaced relation to each other directly on the offset extending end portions of one brake beam adjacent to the outer faces of the side frames, a live brake lever and a brake shoe pivoted centrally in spaced relation directly on the offset extending end portions of the other brake beam, a bar pivotally attached to the lower ends of the dead and live brake levers on each outer side of the truck for connecting said brake levers together, a link pivotally connected to the top end of each dead brake lever and the other end to the truck frame, a brake equalizer bar extending through the side frame and supported therein connecting the top ends of the live truck levers together, an operating lever for actuating the brake mechanism, a flexible connection between the operating lever and the brake equalizer bar, a sheave for guiding the flexible connection, and resilient means interposed between the flexible connection and the operating lever.

8. In a brake rigging for railway car trucks having side frames and two pairs of wheels, a brake beam mounted adjacent to the inner side of each pair of wheels, said brake beams having their end portions extending through and supported by the side frames, a brake lever and a brake shoe head having their central portions pivotally mounted directly on each extending end portion of the brake beams at the opposite outer sides of the truck frame, means for directly connecting the lower ends of the brake levers together on each outer side of the truck frame, an equalizer bar mounted between the pairs of wheels having its ends extending through slots in the side frame and supported therein, clevis members connecting the ends of the equalizer with a pair of brake levers, and means connected to the equalizer bar for actuating the brake mechanism.

40 9. In a brake rigging for railway car trucks having side frames and two pairs of wheels, a brake beam mounted adjacent to the inner side of each pair of wheels, said brake beams having their end portions extending through and supported by the side frames, a dead brake lever and a brake shoe head having their central portions pivotally mounted directly on each extending end portion of one brake beam at the opposite outer sides of the truck frame, a live brake lever and a brake shoe head having their central portions pivotally mounted directly on each extending end portion of the other brake beam at the opposite outer sides of the truck frame, a bar for connecting the lower ends of the dead and live brake levers together on each outer side of the truck frame, a pivoted link connection between the top of each dead truck lever and the outer side of the truck frame, an equalizer bar mounted between the pairs of wheels having its ends extending through slots in the side frame and supported therein, clevis members connecting the ends of the equalizer bar with the pair of live truck levers, an operating lever for actuating the brake mechanism, a flexible connection between the operating lever and the brake equalizer bar, a sheave for guiding the flexible connection, and resilient means interposed between the flexible connection and the operating lever.
